UNITED STATES PATENT OFFICE.

HARRY L. JOHNSON, OF BATTLE CREEK, MICHIGAN.

CARTON MAKING AND SEALING MACHINE.

1,096,918.

Specification of Letters Patent. Patented May 19, 1914.

Application filed August 21, 1912. Serial No. 716,178.

To all whom it may concern:

Be it known that I, HARRY L. JOHNSON, a citizen of the United States, residing at the city of Battle Creek, county of Calhoun, and State of Michigan, have invented certain new and useful Improvements in Carton Making and Sealing Machines, of which the following is a specification.

This invention relates to improvements in carton making and sealing machines.

The main objects of this invention are: First, to provide a combination carton making and top sealing machine. Second, to provide a combination carton making and sealing machine which may be used for making cartons and sealing filled cartons simultaneously, or for making cartons or for sealing only, as desired. Third, to provide an improved machine adapted for these purposes which is entirely automatic. Fourth, to provide an improved machine possessing these advantages which is very compact, and, at the same time, is of large capacity. Fifth, to provide an improved carton making and sealing machine which is comparatively simple and economical in structure and very easy to operate.

Further objects, and objects relating to structural details will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

Figure I is a side elevation of a structure embodying the features of my invention, a portion only of the sealed carton delivery conveyer 18 being illustrated. Fig. II is a plan view of a structure appearing in Fig. I. Fig. III is a horizontal section on a line corresponding to line 3—3 of Fig. V. Fig. IV is a front elevation. Fig. V is a longitudinal vertical section on a line corresponding to line 5—5 of Fig. IV, the conveyer and certain other parts being shown in full lines in order to better illustrate the details thereof. Fig. VI is a detail section on a line corresponding to line 6—6 of Fig. VII, showing the driving gear for one set of the rollers. Fig. VII is a detail vertical section on a line corresponding to the broken line 7—7 of Fig. III. Fig. VIII is a detail vertical

section on a line corresponding to line 8—8 of Fig. II showing details of the flap closing mechanism, a carton being shown on the form, 12. Fig. IX is a detail horizontal section on a line corresponding to line 9—9 of Fig. VIII. Fig. X is a detail view of the carton form or carrier 12 showing the lever 102 for throwing out the side of the carton to permit the securing flap being folded under the same. Fig. XI is an enlarged detail vertical section on a line corresponding to line 11—11 of Fig. II showing details of the blank feed mechanism. Fig. XII is a detail horizontal section on a line corresponding to line 12—12 of Fig. V showing details of the friction means for the blank feed belts. Fig. XIII is a detail view of the carton folding mechanism, partially in section on lines 13—13 of Figs. IV and XVI. Fig. XIV is a detail vertical section on a line corresponding to line 14—14 of Fig. XIII. Fig. XV is a transverse section on a line corresponding to line 15—15 of Fig. XIII. Fig. XVI is a detail elevation view of the carton folding member 76. Fig. XVII is a sectional view of the carton folding member 76 on a line corresponding to line 17—17 of Fig. XVI. Fig. XVIII is a detail section on a line corresponding to line 18—18 of Fig. XVI. Fig. XIX is a detail horizontal section on a line corresponding to line 19—19 of Fig. I, showing details of the carton delivery mechanism. Fig. XX is a detail section on a line corresponding to the broken line 20—20 of Fig. XIX. Fig. XXI is a detail view showing the flap turner or folder 63. Fig. XXII is a plan view of a blank for a carton such as the machine illustrated is especially designed to manufacture.

In the drawing, similar reference characters refer to similar parts throughout the several views, and the sectional views are taken looking in the direction of the little arrows at the ends of the section lines.

Referring to the drawing, the frame of the structure illustrated, comprises a pair of base members, 1, 1, connected by cross pieces 2 and 3 and having suitable feet 4. Side members 5 are mounted on the cross pieces 3, the side members being connected by suitable cross pieces to provide a rigid frame to support the mechanism and the driving connections therefor. Disposed centrally and longitudinally of the frame, is a conveyer way comprising a top member 6 and a bottom member 7, the top member 6 being ar-

ranged above the frame cross pieces 3 while the bottom member 7 is arranged below the same. The conveyer chain 8 is supported on suitable sprockets 9 and 10 arranged at the 5 ends of the conveyer way. See Fig. V.

The links carrying the carton frames or carriers are provided with supports 11 which engage grooves in the sides of the way members to support the frames or carriers in an 10 upright position, while the cartons carried thereby are acted upon by the carton folding and sealing mechanism. The structural details of the conveyer way and these guides or supports are preferably those described in 15 my application for patent on carton sealing machine, filed January 27, 1912, Ser. No. 673,723, and as such details form no part of my present invention I do not further illustrate or describe the same herein.

20 Carton forms or carriers 12, and flights or carriers 13, are mounted on the carrier chain in an alternating relation, the forms 12 being the forms on which the cartons are formed and carried through the sealing 25 mechanism, while the flights or carriers 13 are the carriers which the filled cartons are carried through the sealing mechanism.

The forms 12 are preferably open frames provided with perforations 14 in their 30 outer ends so that the cartons may be ejected by means of compressed air, the sprocket 10 being provided with a nozzle-like tooth adapted to engage the links on which the forms 12 are mounted. This 35 sprocket is connected by the pipe 15 to the pressure tank 16 which is supplied with air through the pump 17.

The ejecting mechanism is that described and claimed in my application for patent 40 referred to and as its details form no part of this invention, I do not illustrate or describe the same herein.

The sealed cartons are discharged at the rear of the machine into the delivery conveyer, designated generally by the numeral 45 18. See Fig. I.

I will first describe the carton making mechanism and then the sealing of the cartons, as the end flap closing and sealing 50 mechanism employed in making the cartons is also utilized for sealing the filled cartons.

The carton blanks having been previously slit to provide flaps and scored to facilitate folding as shown in Fig. XXII are placed 55 in a stack upon the table 19 in position so that the lower edge of the top blank of the stack on the table is engaged by the feed wheels 20. The structure illustrated is provided with four of these feed wheels. The 60 feed wheels 20 are provided with friction lugs 21, see Figs. V and XI, positioned so that a blank is fed at each revolution of the feed wheels. These friction lugs are preferably rubber blocks arranged in suitable 65 seats 22 provided therefor in the wheel rims

and adjustably supported in the seats by means of the screws 23 which engage the follower disks 24. In front of the table and substantially in the plane thereof so that the blanks readily pass from the table thereto, is a friction feed plate 25 having a rubber facing 26. This feed plate is positioned to support the blanks at the point of engagement of the friction lugs 21 of the feed wheels therewith. The feed plate is carried by the arms 27 on the rod 28 extending across the frame, the plate being adjustably mounted on these arms. This adjustment is secured by mounting the plate on the pivots 29 on the arms and providing screws 30 which are arranged through ears 31 on the plate and engage threaded lugs 32 on the arms 27. By means of this adjustment, the friction may be very accurately adjusted so as to secure a positive and accurate feed for 85 the blanks. The blanks are delivered by the feed wheels between the feed belts 33 and 34. The feed belts 34 are arranged on pulleys 35 and 36. The pulleys are disposed below the feed wheels. The feed belts 33 are carried by the pulleys 37 which are mounted on the shaft 38 of the feed wheels and the pulleys 39 on the shaft 40 arranged parallel with the shaft 41 for the pulleys 36. The pulleys 35 and 37 are so disposed that the 90 belts 33 travel over the belts 34 as they pass over their supporting pulleys 36 to receive the carton blanks from the feed wheels and deliver the same to the forms.

To support the feed belts between their 100 pulleys and secure the desired amount of friction on the feed belts, I provide a pressure means consisting of pairs of plates 44 and 45, the plates 44 being carried by cross bars 46 arranged within the belts 34, the plates 45 being carried by blocks 47 adjustably mounted on the cross bars 48 arranged within the belts 33 by means of the adjusting screws 47', see Figs. V and XII, the belts passing between the plates as 105 clearly shown in Fig. XII. By this means, the belts are supported between the pulleys at the point where they engage the carton blanks and their frictional engagement with the blanks may be nicely regulated so that 110 the blanks are fed positively. The blanks are also provided with belt tighteners 49.

The feed wheels and feed belts are driven from the shaft 43 which is connected by the sprocket chain 50 and the sprocket wheel 51 on the shaft 43 to the sprocket wheel 52 on the shaft 53. The driving shaft 54 is provided with tight and loose pulleys 55 and 56. The shaft 54 is connected by the shaft 169 and the gears 170, 171, 172 and 173, the sprocket 174 and sprocket chain 57 to the sprocket 58 on the shaft 59 at the rear of the machine. The conveyer driving sprocket 9 is mounted on this shaft 59. The shaft 59 is connected by the sprocket chain 120 125 130

60 to the shaft 61. On the shaft 61 is a gear 62 meshing with the gear 63 on the shaft 53. The gear 172 is provided with a shifting lever 175 by means of which the 5 mechanism is thrown into and out of gear. By these connections, the feed wheels and feed belts are properly timed with the conveyor so that the carton blanks are delivered to the forms 12 and are carried along there- 10 by through the folding and sealing mechanism.

As the blanks are carried down by the feed belts, the securing flap 64 is engaged by the flap turner 65,—see Figs. IV and 15 XXI,—and folded upon the bar like support 66 so as to present the face of the flaps to the glue wheel 67. The support 66 supports the flap while it is acted upon by the glue wheel. When the securing flap is released 20 it swings out again as there is nothing to retain it in the position in which it receives the glue. The glue tank 68 is arranged to properly deliver the glue to the glue wheel. The glue wheel is driven by the sprocket 25 chain 69 and suitable sprockets on the glue wheel and the driving shaft 54. The mechanism is timed so that the blanks are fed down in front of the forms 12, their lower edges being supported by the rest 70 thereof. 30 The carton blanks are carried by the forms between the rollers 71 and 71', 71' which are arranged at the sides of the conveyor. This folds the side portions 72 and 73 of the blanks against the form, the side portion 74 being engaged by the front of the form. The rollers 71' are aligned, being in effect a sectional roller, the two rollers being employed to accommodate the folder member 76. As the side portion 73 of the car- 35 ton is swung into position, the side portion 75 is engaged by the folder member 76 and swung against the form. The folder member 76 is provided with rollers 77, the member being forked and provided with a spin- 40 dle 78 by which the rollers are carried,—see Figs. XVI and XVII. On the spindle 78 is a sleeve 79 which serves as a bearing for the rollers 77. On the sleeve 79 are fingers 80 which are actuated at the proper 45 time to fold the securing flap 64 under the side portion 72.

The member 76 is carried by an arm 81 on the slide 82. To provide a forward and lateral movement for the member 76, the 50 slide 82 is mounted in a carriage 83 mounted on rod-like ways 84. The carriage is moved back and forth on these ways and the slide reciprocated by means of the cam grooves 85 on the bracket or supporting plate 86 on 55 which the rods 84 are mounted, the slide 82 is provided with a pin 87 engaging the cam. The shaft 88 is provided with a slotted arm 89 engaging the pin 87 so that as the shaft 60 is revolved, the pin is carried around in the cam groove, thus reciprocating the slide car-

rying the folder member 76 and also the carriage. The shaft 88 is provided with a sprocket 90 connected by the sprocket chain 91 to a sprocket 92 which is connected by means which will appear as the description 70 proceeds so that the actuation of the folder member is properly timed.

The flap folding fingers 80 are actuated to fold the securing flap 64 under the side por- 75 tions 72. I accomplish this by means of the rack 93 coacting with the pinions 94 on the sleeve 79 by which the fingers are carried. The rack is connected by a link 95 to the lever 96 pivoted at 97 on the arm 81 of the slide 82, the lever is connected by a link 98 80 to the rack slide or actuating member 99 having a limited movement independent of the slide 82 so that just prior to the time the slide 82 reaches the limit of its stroke the stop 100 of the actuating member 99 85 engages and the continued movement of the slide 82 actuates the rack 93. The rack 93 is mounted in a slide-way 101 on the mem- 90 ber 76. See Fig. XVIII. The stop 100 for the actuating member 99 is preferably ad- justable as shown in Fig. XIV.

To insure the folding of the securing flap 64 inside of the side portion 72, the forms 12 are provided with levers 102 arranged to force the rear edge of the side wall 72 out- 95 ward when the lever is actuated. The lever 102 is actuated by the lever 103 which is pivoted at 104 to engage the lever 102. See Figs. III and X. The lever 103 is ac- 100 tuated by the cam 105.

As the carton is carried between the folding rollers 71, 71' described, its side portion 72 is pressed down on the glued flap 64. The carton is then carried between the pressure rollers 106 arranged vertically at 105 each side of the conveyor so that the car- 110 tons are carried along between the same. These rollers are connected by trains of gears designated generally by the numeral 107, see Figs. VI and VII. The trains of gears 107 are driven from the gears 108 on the shafts 109 and 109'. The train of gears 107 is shown in detail in Fig. VI, the gears being arranged so that the rollers are all driven in a forward direction, the object 115 being to obviate friction of the rollers on the sides of the carton as it is carried along.

The shafts 109 and 109' are provided with sprockets 110 which are connected by the sprocket chains 111 to sprockets 112 driven 120 through the gears 112' on the vertical shafts 113 at the rear of the machine.

The sprocket 92 for the folder mechanism driving chain 91 is carried by gears 92' to 125 the shaft 109.

As the cartons leave the pressure rollers, the inner rear flap is engaged by the flap folder 114, and folded forwardly under the front inner flap. See Fig. VIII. This fold- 130 ing is timed so that it is effected just pre-

vious to the engagement of the folding of the front inner flap by the flap folder and retainer 115 which is a fixed horizontal bar-like member turned upwardly at its forward end so that the flap is pressed down and retained as the carton is carried along under the same.

The flap folder 114 is mounted on the rock-shaft 116 which is provided with a 10 segment 117 driven through the curved rack 118 carried by an arm on the rock-shaft 119, the object being to actuate the flap folder with a quick stroke so that the flap is folded forwardly as the carton is carried along. 15 See Figs. V and VIII. The rock shaft 119 is provided with an arm 120 connected by the link 121 to the lever 122 pivoted at 123 to be actuated by the cam wheel 124 which is provided with a cam groove in its inner 20 face to engage the arm. See Figs. I and III.

As the cartons are carried under the folder 115 the outer or side flaps are engaged by the spreaders or guides 125 arranged at each side of the flap folding and retaining member 115. These spreaders or guides are preferably formed of an A-shaped rod arranged through the support 126. The guides or spreaders are inclined 25 rearwardly to spread and guide the side flaps to the glue rollers 127. The side flaps are supported as they pass under the glue rollers by the rollers 128. These supporting rollers and flap guides and glue rollers are 30 preferably as shown in my co-pending application referred to and therefore are not described with further detail herein.

After the cartons pass the glue rollers, the side flaps are folded and sealed upon the 40 inner flaps by the flap folders 129 and the flap pressers 130. As these flap folders 129 which are shaped somewhat like a mold board, engage under the side flaps and fold them inward one upon the other, the flap 45 folders and pressers being arranged alternately so that one flap is turned and pressed upon the inner flaps and the other is turned and pressed upon such flap. The flap pressers are driven by the shafts 176 which are connected by suitable sprockets 177 and 178 and the chains 179 to the shafts 113. As 50 these flap folders and pressers are of the type illustrated in my co-pending application referred to and as their structural details form no part of my present invention, I do not describe the same with further detail herein.

After passing the flap folders, the closed and sealed flaps are engaged by the curved 60 flap retaining bar 131 which retains them in their sealed position until they are engaged by the pressure rollers 132, the objects of placing these rollers some distance from the sealing point being to give the glue or other 65 adhesive employed time to partially set.

The rollers 132 are connected by a train of gears 133 so that they are all driven in the same direction. One of the rollers is provided with a sprocket connected by the sprocket chain 134 to a sprocket on the shaft 51. After passing the pressure rollers 132 the flaps are engaged by the retainer 135 which prevents their opening until the cartons are ejected from the carrier formed by the pneumatic means stated.

I will now describe the carton sealing mechanism, that is, the mechanism for sealing the filled cartons.

The filled cartons are carried into the machine by the belt 136 carried by the pulley 137 supported in the arm 138 projecting out of the front of the machine and the pulley on the stub shaft 139 positioned so that the belt is supported alongside of the table 140.

The shifter 141 is slidably mounted on the rock-shaft 119 and is actuated by the bell crank lever 142 pivoted at 143 and connected by the link 144 to the shifter and by the link 145 to the actuating lever 146. This actuating lever is pivoted at 147 to be engaged by the cam wheel 148 having a cam groove on its inner side. This cam wheel is mounted on the outer end of the shaft 59 so that the actuation of the shifter is properly timed. The filled cartons are shifted from the feed belt on to the conveyer carriers or flights 13. The filled cartons may be delivered to the feed belt of any suitable conveyer or by hand, as desired, and in practice are delivered from a filling machine directly on the belt. The shifting mechanism in detail is preferably that described and claimed in my application for patent, Serial No. 446,893, and I do not herefore illustrate the same with further detail herein.

As the filled cartons are carried along by the conveyer, the top flaps are folded and sealed by the mechanism described for folding the bottom flaps in the manufacture of the carton.

At the rear end of the machine, the sealed cartons are discharged to the delivery conveyer 18 instead of being carried to the front end of the machine to be discharged as are the empty cartons. The mechanism 115 for effecting this discharge of the filled sealed cartons comprises the discharge belts 150 arranged in opposed pairs at the rear end of the conveyer. The discharge belts are actuated to engage the filled sealed cartons 120 and permit the empty cartons to pass onward to the front end of the machine where they are ejected as described.

The belts 150 are carried by pulleys 151 and 152, the pulleys 152 being mounted on the vertical shafts 153 carried by the swinging frame 154. These swinging frames are mounted on the vertical shafts 113. The shafts 113 are provided with beveled gears 155 which mesh with gears 156 on the shaft 130.

59. The pulleys 151 are fixed to the shafts 113 to drive the belts. The frames are swung to and from engaging position by the cam wheels 157 having cam grooves in their under sides coacting with the rollers 158 on the arms 159.

The cam wheels 159 are mounted on vertical shafts 160 journaled in the swinging frames 154. These shafts are connected by the gears 161 and the gears 162 to the shafts 113 so as to be driven thereby and properly timed with the conveyer, the driving pulley 9 of which is mounted on the shaft 59, as described. By this arrangement, the frames 15 are swung from their engaging position to permit the unfilled cartons to pass and to their engaging position to engage the filled cartons and deliver the same to the delivery conveyer 18.

20 To insure positive gripping of the packages by the belts I provide belt supports comprising the supporting bars 163 arranged between the pulleys and carried by the cross bars 164 mounted on the bars 165. 25 The bars 163 are carried by the blocks 166 on the shafts 153. The pulleys 152 are loosely mounted on these shafts and the shafts are pivoted in the frames to permit the swinging of the belt supports.

30 The belt supports are actuated by cams 167 on the gears 161 which engage rollers 168 on the belt supporting bars 165 so that as the gears 161 are revolved the belts are swung toward each other to engage the cartons 35 carried by the conveyer carriers 13, the belts being swung apart to permit the cartons carried by the forms 12 to pass on to the front of the machine.

While the machine illustrated manufactures the cartons directly from the blanks, the structure can be modified by omitting the blank feeding mechanism and the mechanism for folding the blank upon the forms to receive cartons whose securing flaps 64 45 have been previously secured, as is the case in the structure shown in my application for patent referred to. In such a modified structure the cartons are placed upon the conveyer carriers by hand.

50 I have illustrated and described my improvements in a practical embodiment. I have not attempted to illustrate or describe various modifications and adaptations which I contemplate as I believe such modifications and adaptations will be readily understood by those skilled in the art to which this invention relates from the disclosure made. I desire, however, to be understood as claiming my invention specifically in the form 55 illustrated as well as broadly within the scope of the appended claims.

Having thus described my invention, what I claim as new and desire to secure by Letters Patent is:

65 1. In a structure of the class described,

the combination with the conveyer having forms thereon, of a blank feeding means timed to feed the blanks to the front sides of the forms, a securing flap gluing means arranged to apply the glue as the blank is fed to the forms, folding rollers disposed at the sides of the conveyer to fold the blank against the sides of the form, a folder member for the rear side of the carton provided with a carton engaging roller and securing flap folding fingers, means for actuating said folder member with a lateral and forward movement and for actuating said flap folding fingers at the end of its stroke, side extending levers carried by said forms, means for actuating said levers to extend the side of the carton so that the securing flap is folded under the same prior to the passing through said folding rollers whereby the side is pressed against the glued flap, a series of pressure rollers arranged at the rear of said folding rollers, and end flap closing and sealing mechanism positioned to act on the carton as it is carried along by the conveyer.

2. In a structure of the class described, the combination with the conveyer having forms thereon, of a blank feeding means timed to feed the blanks to the front sides of the forms, a securing flap gluing means arranged to apply the glue as the blank is fed to the forms, folding rollers disposed at the sides of the conveyer to fold the blank against the sides of the form, a folder member for the rear side of the carton provided with a carton engaging roller and securing flap folding fingers, means for actuating said folder member with a lateral and forward movement and for actuating said flap folding fingers at the end of its stroke, side extending levers carried by said forms, and means for actuating said levers to extend the side of the carton so that the securing flap is folded under the same prior to the passing through said folding rollers whereby the side is pressed against the glued flap.

3. In a structure of the class described, the combination with the conveyer having forms thereon, of a blank feeding means timed to feed the blanks to the front sides of the forms, a securing flap gluing means arranged to apply the glue as the blank is fed to the form, folding rollers disposed at the sides of the conveyer to fold the blank against the sides of the form, a folder member for the rear side of the carton provided with a securing flap folding finger, means for actuating said folder member and its flap folding finger to fold the flap under the adjacent side prior to its passing through the folding rollers, a series of pressure rollers arranged at the rear of said folding rollers, and end flap closing and sealing mechanism positioned to act on the carton as it is carried along by the conveyer.

4. In a structure of the class described, the combination with the conveyer having forms thereon, of a blank feeding means timed to feed the blanks to the front sides 5 of the forms, a securing flap gluing means arranged to apply the glue as the blank is fed to the form, folding rollers disposed at the sides of the conveyer to fold the blank against the sides of the form, a folder member 10 for the rear side of the carton provided with a securing flap folding finger, and means for actuating said folder member and its flap folding finger to fold the flap under the adjacent side prior to its passing 15 through the folding rollers.

5. In a structure of the class described, the combination with the conveyer having forms thereon, of a blank feeding means timed to feed the blanks to the front sides 20 of the forms, a securing flap gluing means, means for folding the blank against the sides of the form, a folder member for the rear side of the carton provided with securing flap folding finger, means for actuating 25 said folder member and its said finger, side extending members carried by said forms, means for actuating said members to extend the side of the carton so that the securing flap is folded under the same, and 30 end flap closing and sealing mechanism positioned to act on the carton as it is carried along by the conveyer.

6. In a structure of the class described, the combination with the conveyer having 35 forms thereon, of a blank feeding means timed to feed the blanks to the front sides of the forms, a securing flap gluing means, means for folding the blank against the sides of the form, a folder member for the 40 rear side of the carton provided with securing flap folding finger, means for actuating said folder member and its said finger, side extending members carried by said forms, and means for actuating said members 45 to extend the side of the carton so that the securing flap is folded under the same.

7. In a structure of the class described, the combination with the conveyer having forms thereon, of a blank feeding means 50 timed to feed the blanks to the front sides of the forms, a securing flap gluing means, means for folding the blanks against the sides of the forms, a folder member for the rear side of the carton provided with a 55 carton engaging roller and securing flap folding fingers, and means for actuating said folder member with a lateral and forward movement and for actuating said folding fingers at the end of its stroke.

8. In a structure of the class described, the combination with the conveyer having forms thereon, a securing flap gluing means, a folder member provided with securing flap folding means, means for actuating

said folder member and its said flap folding 65 means, side extending members carried by said forms, and means for actuating said members to extend the side of the carton so that the securing flap is folded under the same. 70

9. In a structure of the class described, the combination with the conveyer having forms thereon, a flap gluing means, a flap folder member provided with a carton engaging roller and with a flap folding finger, 75 and means for actuating said member with a lateral and forward movement and for actuating said flap folding finger at the end of its stroke.

10. In a structure of the class described, 80 the combination with the conveyer having forms thereon, means for folding the blank and the securing flap upon the form, side extending levers carried by said forms, and means for actuating said levers to extend 35 the side of the carton so that the securing flap is folded under the same.

11. In a structure of the class described, the combination with the conveyer having forms thereon, means for folding the blank 90 and the securing flap upon the form, side extending members carried by said forms, and means for actuating said members to extend the side of the carton so that the securing flap is folded under the same. 95

12. In a structure of the class described, the combination of a folder member, a spindle carried thereby, a sleeve on said spindle, rollers loosely mounted on said sleeve, fingers on said sleeve, a pinion on said sleeve, 100 a rack slidably mounted on said folder member to coact with said pinion, a carriage, ways for said carriage, a slide by which said folder member is carried mounted on said carriage, a cam, a pin on said slide 105 engaging said cam, a shaft having a slotted arm engaging said pin whereby said folder member slide is reciprocated and said carriage actuated on its way, a rack slide provided with stops, a lever pivoted on said 110 folder member slide, and links connecting said lever to said rack and its slide, all coacting for the purpose specified.

13. In a structure of the class described, the combination of a folder member, a finger mounted on said folder member, a pinion connected to said finger, a rack slidably mounted on said folder member to coact 115 with said finger, a carriage, a way for said carriage, a slide by which said folder member is carried mounted on said carriage, a cam, a pin on said slide engaging said cam, a shaft having a slotted arm engaging said pin whereby said folder member slide is reciprocated and said carriage actuated on its 120 way, a rack slide provided with stops, a lever pivoted on said folder member slide, and links connecting said lever to said rack.

and its slide, all coacting for the purpose specified.

14. In a structure of the class described, the combination of a folder member, a spindle carried thereby, a sleeve on said spindle, a roller loosely mounted on said sleeve, a finger on said sleeve, a pinion on said sleeve, a rack slidably mounted on said folder member to coact with said pinion, a slide 10 by which said folder member is carried, means for reciprocating said slide, a rack slide provided with stops, a lever pivoted on said folder member slide, and links connecting said lever to said rack and its slide, all 15 coacting for the purpose specified.

15. In a structure of the class described, the combination of a folder member having a flap folding finger thereon, a pinion connected to said finger, a rack slidably mounted on said folder member to coact with said pinion, a slide by which said folder member is carried mounted on said carriage, means for reciprocating said slide, a rack slide provided with stops, a lever pivoted on said 25 folder member slide, and links connecting said lever to said rack and its said slide, all coacting for the purpose specified.

16. In a structure of the class described, the combination with the endless conveyer 30 provided with alternate carton forms and carton carrier flights, carton blank folding and sealing mechanisms, means for feeding filled cartons to the flights at the rear of said carton blank folding and sealing mechanisms, and flap closing and sealing means 35 adapted to close and seal the end flaps of the cartons carried by the forms and flights.

17. In a structure of the class described, the combination with the endless conveyer 40 provided with alternate carton forms and carton carrier flights, a blank feeding means for delivering the blanks to said forms, carton blank folding and sealing mechanism, means for feeding filled cartons to the 45 flights at the rear of said carton blank folding and sealing mechanism, flap closing and sealing means adapted to close and seal the ends of the cartons carried by the forms and flights, and means for discharging the filled 50 cartons at one point of the travel of the conveyer and means for discharging the cartons carried by the forms at another point in the travel of the conveyer.

18. In a structure of the class described, 55 the combination with the endless conveyer provided with alternate carton forms and carton carrier flights, a blank feeding means for delivering the blanks to said forms, carton blank folding and sealing mechanism, means for feeding filled cartons to the flights at the rear of said carton blank folding and sealing mechanism, flap closing and sealing means adapted to close and seal the end flaps of the cartons carried by the 60

forms and flights, a discharge mechanism 65 for the filled cartons adapted to discharge the cartons carried by the flights at the rear of the machine and permit the cartons carried by the forms to return to the front of the machine, and means for ejecting the cartons from said forms at the front of the machine.

19. In a structure of the class described, the combination with the endless conveyer provided with alternate carton forms and 70 carton carrier flights, a blank feeding means for delivering the blanks to said forms, carton blank folding and sealing mechanism, means for feeding filled cartons to the flights at the rear of said carton folding and sealing mechanism, flap closing and sealing means 75 adapted to close and seal the end flaps of the cartons carried by the forms and flights, and a discharge mechanism for the filled cartons adapted to discharge the cartons carried by the flights and permit the cartons carried by the forms to pass.

20. In a structure of the class described, the combination with the conveyer provided 80 with carton forms and carton carriers or flights, a blank feeding means for delivering the blanks to said forms, carton blank folding and sealing mechanism, means for feeding filled cartons to the flights at the rear of said carton blank folding and sealing 85 mechanism, flap closing and sealing means adapted to close and seal the end flaps of the cartons carried by the forms and flights, means for discharging the filled cartons at one point of the conveyer travel, and means 90 for discharging the cartons from the forms at another point of the conveyer travel.

21. In a structure of the class described, the combination with the conveyer provided 95 with carton forms and filled carton carrier flights, carton blank folding and sealing mechanism, means for feeding filled cartons to the flights at the rear of said carton folding and sealing mechanism, flap closing and sealing means adapted to close and seal the 100 end flaps of the cartons carried by the forms and flights, a discharge mechanism for the filled cartons adapted to discharge the cartons carried by the flights at the rear of the machine and permit the cartons carried by 105 the forms to return to the front of the machine, and means for ejecting the cartons from said forms at the front of the machine.

22. In a structure of the class described, the combination with the conveyer provided 110 with carton forms and filled carton carrier flights, carton blank folding and sealing mechanism, means for feeding filled cartons to the flights at the rear of said carton folding and sealing mechanism, flap closing and 115 sealing means adapted to close and seal the end flaps of the cartons carried by the forms and flights, a discharge mechanism for the 120

filled cartons adapted to discharge the cartons carried by the flights and permit the cartons carried by the forms to pass, and means for ejecting the cartons from said forms.

23. In a structure of the class described, the combination with the conveyer provided with carton forms and filled carton carrier flights, carton blank folding and sealing mechanism, means for feeding filled cartons to the flights at the rear of said carton folding and sealing mechanism, flap closing and sealing means adapted to close and seal the end flaps of the cartons carried by the forms and flights, means for discharging the filled cartons at one point of the conveyer travel, and means for discharging the cartons from the forms at another point of the conveyer travel.

24. In a structure of the class described, the combination with the conveyer provided with alternate carton forms and carton carriers or flights, a conveyer shaft, means for discharging the cartons carried by the conveyer, means for discharging the cartons carried by the flights comprising belts arranged in opposed pairs at the sides of the conveyer, vertical shafts arranged one at each side of the conveyer and geared to said conveyer shaft, swinging frames mounted on said vertical shafts, pulley shafts on said swing frames, pulleys for said belts mounted on said vertical shafts carried by said swinging frames, cam shafts carried by said swinging frames, gears connecting said cam shafts to said vertical shafts, cams on said cam shafts, and members coacting with said cams to swing said frames as the cams are revolved, all coacting for the purpose specified.

25. In a structure of the class described, the combination with the conveyer provided with alternate carton forms and carton carriers or flights, a conveyer shaft, means for discharging the cartons carried by the conveyer, means for discharging the cartons carried by the flights comprising belts arranged in opposed pairs at the sides of the conveyer, vertical shafts arranged one at each side of the conveyer and geared to said conveyer shaft, swinging frames mounted on said vertical shafts, pulley shafts on said swing frames, pulleys for said belts mounted on said vertical shafts and said shafts carried by said swinging frames, cams for said swinging frames geared to said driven shafts, belt supports comprising belt engaging members and supports therefor mounted at their outer ends on said pulley shafts carried by said swing frames, and cams arranged to act on said belt supports, all coacting for the purpose specified.

26. In a structure of the class described,

carried by the flights comprising belts arranged in opposed pairs at the sides of the conveyer, vertical shafts arranged one at each side of the conveyer and geared to said conveyer shaft, swinging frames mounted on said vertical shafts, pulley shafts on said swing frames, pulleys for said belts mounted on said vertical shafts carried by said swinging frames, cam shafts carried by said swinging frames, gears connecting said cam shafts to said vertical shafts, cams on said cam shafts, and members coacting with said cams to swing said frames as the cams are revolved, all coacting for the purpose specified.

27. In a structure of the class described, the combination with the conveyer provided with alternate carton forms and carton carriers or flights, a conveyer shaft, means for discharging the cartons carried by the flights comprising opposed belts, driven shafts, swinging frames mounted on said driven shafts, pulley shafts on said swing frames, pulleys for said belts mounted on said driven shafts and said shafts carried by said swinging frames, cams for said swinging frames geared to said driven shafts, belt supports comprising belt engaging members and supports therefor mounted at their outer ends on said pulley shafts carried by said swing frames, and cams arranged to act on said belt supports, all coacting for the purpose specified.

28. In a structure of the class described, the combination with the conveyer provided with alternate carton forms and carton carriers or flights, a conveyer shaft, means for discharging the cartons carried by the flights comprising opposed belts, driven shafts, swinging frames mounted on said driven shafts and said shafts carried by said swinging frames, and cams for said swinging frames geared to said driven shafts, all coacting for the purpose specified.

In witness whereof, I have hereunto set my hand and seal in the presence of two witnesses.

HARRY L. JOHNSON. [L. s.]

Witnesses:

F. L. CONDON,
Geo. C. MCKAY.
